UNITED STATES PATENT OFFICE.

OTTO PEARSON, OF MOUNT JEWETT, PENNSYLVANIA.

SLED-RUNNER CONNECTING-BENCH.

1,186,825.

Specification of Letters Patent. Patented June 13, 1916.

Application filed February 26, 1915. Serial No. 10,771.

To all whom it may concern:

Be it known that I, OTTO PEARSON, a subject of the King of Sweden, residing at Mount Jewett, in the county of McKean and State of Pennsylvania, have invented certain new and useful Improvements in Sled-Runner Connecting-Benches; and I do declare the following to be a full, clear, and exact description of the invention, such as will enable others skilled in the art to which it appertains to make and use the same.

This invention relates to improvements in sleds and more particularly to hand or coasting sleds.

15 The main object of the invention is to provide an improved sled which may be assembled and all of the parts connected without the use of any rivets or similar detachable fastening elements, thereby greatly 20 cheapening the construction of the sled.

Another object of the invention is to provide simple and efficient means for securing the runner supporting knees or standards to a sled top or body.

25 Another object is to provide a simply constructed and efficient cross bar for connecting the front ends of the side bars or arms of the sled top without the use of rivets.

Another object is to provide improved 30 means for connecting the rear ends of the runners to the sled top.

With the above and other objects in view, the invention consists of certain novel features of construction, combination and arrangement of parts as will be more fully described and claimed and shown in the drawings wherein:

Figure 1 is a side elevation of a sled equipped with these improvements; Fig. 2 is a longitudinal central section thereof; Fig. 3 is a bottom plan view thereof; Fig. 4 is a detail top plan view of the front portion of the sled; Fig. 5 is a transverse section taken on the line 5—5 of Fig. 1; Fig. 6 is a detail 45 perspective view of the plates constituting the cross bar of the bench arranged in juxtaposition ready for assembling; Fig. 7 is a detail perspective view of the one-piece runner, standards, and cross bars; Fig. 8 is 50 a detail side elevation showing a slightly different form of bench; Fig. 9 is a transverse section thereof taken on the line 9—9 of Fig. 8; Fig. 10 is a vertical longitudinal section taken on the line 10—10 of Fig. 9,

and Fig. 11 is a detail perspective view of 55 the blank from which the cross bar or bench shown in Figs. 8 to 10 is formed.

In the embodiment illustrated a sled is shown having a one-piece wooden top 1, although it is obvious that it may be constructed of a plurality of connected pieces or slats if desired. This top 1 has two forwardly projecting side bars or arms 2 and 3 with a forwardly extending tongue 4 disposed between them and terminating about 60 midway the length thereof. This top is supported in the construction shown, by front, rear and central cross bars 5, 6 and 7 made integral with the runners 8 and knees or standards 9 all formed from a 65 single piece of metal of any suitable or desired shape in cross section. This piece of metal is bent intermediate of its ends to form the front cross bar 5 which is here shown flattened intermediate of its ends 70 at the center thereof and slotted longitudinally as shown at 10, said slot opening horizontally and which is designed to receive the steering bar connecting link to be described. This rod or metal bar is then bent 75 laterally from the opposite ends of this cross bar 5 and is curved to form the front ends of the runners and the two members thereof are extended in parallel planes for a pre-determined distance and then bent laterally 80 upward to form one member 11 of the standards or knees 9, the knees at the opposite sides of the sled being of the same length. From the inner ends of these knee members 85 11 extend loops 12 arranged at right angles 90 to the knees and extending inwardly to form the intermediate cross bar 6. These loops 12 extend inwardly toward each other at opposite sides of the top 1 and are secured thereto by a connecting bench 13 to be described. After these loops 12 have been 95 formed, the rod is extended at right angles from the outer ends of the loops to form the other member 14 of the intermediate knee 9, said knees 9 at opposite sides of the sled being each formed of the two members 100 11 and 14 which are connected at their upper ends by the laterally extending loops 12 and which are of the same length so as to position the front and rear portions of the 105 runners in alignment. The two members of the rod are then extended longitudinally rearward from the lower end of the mem-

bers 14 in alinement with the front portions of the runner and are made of any suitable or desired length according to the length of the sled to be constructed. At the rear 5 ends of the rear portions of the runners, the rod is bent inwardly and forwardly to form reinforced ends 15 and from the inner ends of these reinforced portions, the rod is extended upwardly substantially at right 10 angles to form the rear standards or knees 16. The ends of the rod extend inwardly at right angles from the upper ends of the rear knees 16 and are arranged parallel with each other to form the rear bench 17, the 15 terminals of said rod being wrapped around the adjacent parallel member of the bench 17 at the base or upper end of the knee 16, forming eyes 18 whereby the members of said bench are securely connected and these 20 terminals are then driven into the sled top and preferably extended therethrough and clenched on the upper face thereof, thereby securely connecting the rear bench 17 to the top 1 without employing any rivets or other 25 separable fastening elements.

In Figs. 1 to 6, the bench 13 for connecting the loops 12 which constitute the intermediate cross bar 6, is here shown in the form of two substantially rectangular sheet 30 metal plates 19 and 24 as shown in Fig. 6 and connected together. The plate 19 is shown made of heavier metal than plate 24 and is provided midway its width with two pairs of laterally extending tongues 20 and 25 35 and 21 which are struck out of the plate 19 and arranged in longitudinal alinement and which are designed to provide prongs for connecting the bench 13 to the sled body or top as will be presently described. Arranged 40 in the plate 24 opposite the tongues 20 and 21, are two transversely extending slots 22 and 23 which are disposed in longitudinal alinement with each other and register with the pairs of tongues 20 and 21 so that when 45 said plate 19 is placed over plate 24, these slots will register with the tongues and through which said tongues are designed to pass with their terminals projecting beyond the plate 24 to provide attaching prongs 50 which are designed to be driven into the under face of the sled top to assist in securing the bench to the top and which are also designed to connect the loops 12 to the top, the cross bar of each loop being disposed 55 in the space between each of the two pairs of tongues, one loop being disposed between the tongues 20 and the other loop between the tongues 21. (See Fig. 3). The plate 19 has inturned side flanges 19^a which 60 serve to space the plate a desired distance from top 1 (see Fig. 2) and between which plate 24 is designed to lie. Plate 24 has in-turned side flanges 25 which reinforce the edges thereof and serve to retain it in 65 position in plate 19.

To assist in securing this bench 13 to the top 1 for reliably connecting the cross bar to said top, rivets 26 and 27 are shown passing transversely through the opposite ends of the bench 13 and through the top 1, being 70 upset at their outer ends to securely hold the bench in engagement with the top. While these rivets are not absolutely necessary as the tongues 20 and 21 might suffice, for securing the bench 13 to the top 1, yet they 75 are provided as an auxiliary support to prevent accidental detachment of the bench.

In Figs. 8 to 11, the bench 13 is shown constructed from a single plate 19' provided midway its width with two pairs of laterally extending tongues 20' and 21' which are struck out of the plate 19' and arranged in longitudinal alinement and which are designed for securing the loops 12 to the top 1, as will be presently described. Arranged at the opposite edges of the plate 19' opposite the tongues 20' and 21' are two pairs of transversely extending slots 22' and 23' which are disposed in longitudinal alinement with each other and with the 90 tongues 20' and 21' so that when said plate is folded longitudinally on the lines indicated at 24' and 25' these slots will register with the tongues and through which said tongues are designed to pass with their terminals projecting beyond the folded members of the plate 19' and which are designed to be folded flat against the plate as is shown in Fig. 9. This plate 19' is provided at its opposite ends in longitudinal alinement with the tongues 20' and 21' with two longitudinally extending tongues 28 and 29 which are designed to be bent around the opposite side edges of the top 1 and thereby 95 secure the bench reliably to the top without 100 the use of any rivets at all.

A metal link 30 is here shown in the form of a bar or strip secured to the tongue 4 midway the length thereof. This link is fixed intermediately of its ends to the steering bar 31 and projects beyond the front edge of said bar and is bent downwardly and forwardly and then upwardly to form a hook 33 which is adapted to be inserted through the slot 10 of the runner connecting cross bar 5 for connecting the steering bar with said cross bar. This connection of the steering bar with the front cross bar of the runners provides for the bending of said runners laterally in either direction according to the direction in which the steering bar is turned.

By forming the central cross bar 5, of the loops 12, a spring-like structure is provided whereby the movement of the steering bar 110 to either side causes the adjacent side of the loop 12 disposed on that side of the sled to yield and move laterally, thereby avoiding the necessity of bending the runners proper, which permits the runners to be made of 115 120 125 130

ordinary iron and not of spring steel, thereby greatly cheapening the structure of the sled and yet accomplishing the same purpose that is accomplished by the use of steel runners. Upon the release of the steering bar, the loops of the cross bar will spring inwardly to force the runner back into normal position.

A cross bar 34 connects the front ends of the arms 2 and 3 of the top 1 and is here shown constructed of metal having tongues 35 struck laterally upward adjacent the opposite ends thereof and which are designed to pass transversely through the ends of the arms 2 and 3 and be clenched on the upper faces thereof as shown clearly in Fig. 4, thereby securely connecting these arms with said cross bar and avoiding the necessity of using any rivets or similar fastening elements.

In the form of bench shown in Figs. 8 to 11, the tongues 28 and 29 extend in a direction opposite to the tongues 20' and 21' to enable the bench to be secured to the sides 25 of the top 1 without interfering with the operation of the front portions of the runners which will yield laterally at the loops 12 above described. The sides of the plate 19' shown in this form, are folded down- 30 wardly to form securing means for the loops 12 which are housed between said folded members and between the tongues 20' and 21', said tongues being passed through the slots 22' and 23' and folded 35 flat against the plate for securing the folded portions thereof in connected relation.

From the above description, it will be obvious that the sled herein shown may be formed entirely without the use of any 40 rivets while it is preferable that two be employed when the form of bench shown in Figs. 1 to 6 is used, otherwise, no rivets are used throughout the entire construction of the sled and yet all of the parts thereof are 45 securely and reliably connected.

I claim as my invention:—

1. A bench for connecting lateral extensions of sled runner standards to the top of a sled comprising a plate having pairs of laterally projecting prongs for receiving the extensions between them and for penetrating the top to provide for the connection of the plate to the top.

2. A bench for connecting lateral extensions of sled runner standards to the top of a sled comprising a plate having pairs of laterally projecting prongs for receiving the extensions between them and for penetrating the top to provide for the connecting of the plate to the top, said plate having spacing elements extending in the same direction as said prongs to prevent binding of the ex-

tensions between the plate and the sled top when the device is applied.

3. A bench for connecting lateral extensions of sled runner standards to the top of a sled comprising a plurality of superposed members spaced apart to form a housing for said extensions, one member having tongues and the other slots for the passage therethrough of said tongues, said tongues being adapted to receive the standard extensions between them.

4. A bench for connecting lateral extensions of sled runner standards to the top of a sled comprising superposed metal plates, one having a plurality of longitudinally alined laterally extending tongues and the other having transversely extending slots registering with said tongues and through which said tongues extend when the bench is assembled, said bench having means at its ends to provide for its attachment to a sled top.

5. A bench for connecting lateral extensions of sled runner standards to the top of a sled, comprising two substantially rectangular sheet metal plates, one fitting within the other and each provided with inturned side flanges, one of said plates being provided midway its width with pairs of laterally extending tongues struck out of the plate and arranged in longitudinal alinement, the other plate having transversely extending slots disposed in longitudinal alinement with each other and in register with the tongues of the other plate and through which said tongues are designed to pass when the parts are assembled, said tongues being of a length sufficient to project beyond the slotted plate to form penetrating prongs for attaching the bench to a sled top, said tongues being designed to receive between them the lateral extensions of the runner standards.

6. A sled including knees provided with lateral extensions arranged parallel with each other, the end of one extension being bent to form an eye encircling the other extension, the terminals of said extensions being adapted to be extended through the sled top and upset.

7. A sled top including forwardly extending side arms, and a metal cross bar having tongues struck up therefrom and extending through said arms and clenched.

In testimony whereof I have hereunto set my hand in presence of two subscribing witnesses.

OTTO PEARSON.
